DESIGN FOR A MONOGRAM ALPHABET

Olga Dammé, Providence, R. I., assignor to Coro-
Gram Inc., New York, N. Y., a corporation of
New York

Application February 26, 1934, Serial No. 50,884

Term of patent 3½ years

To all whom it may concern:

Be it known that I, OLGA DAMMÉ, a citizen of the United States and resident of Providence, R. I., in the county of Providence and State of Rhode Island, have invented a new, original, and ornamental Design for a Monogram Alphabet, of which the following is a specification, reference being had to the accompanying drawing, forming part thereof.

In the drawing:

Fig. 1 represents a design for a monogram al-

phabet, which is particularly applicable for letters formed from metal or other material, the letters Q and X being omitted.

Fig. 2 is a perspective view of the letter A of the alphabet.

The letters U and V are substantially alike.

I claim:

The ornamental design for a monogram alphabet, substantially as shown and described.

OLGA DAMMÉ.
